UNITED STATES PATENT OFFICE

EDUARD VON SALIS, OF WINTERTHUR, SWITZERLAND, ASSIGNOR TO THE FIRM SULZER
FRÈRES SOCIETE ANONYME, OF WINTERTHUR, SWITZERLAND

FUEL-INJECTION DEVICE FOR INTERNAL-COMBUSTION ENGINES

Application filed August 3, 1929, Serial No. 383,305, and in Switzerland August 10, 1928.

This invention relates to fuel injection devices for internal combustion engines and in particular to apparatus of the kind in which the fuel is accumulated in a charge 5 accumulator having an outlet valve locked in the closed position until the moment when injection is to take place when the valve is opened by the action of the fuel itself.

To this end it has previously been proposed to provide a non-return or throttle valve in a branch pipe between the accumulator and the fuel supply pipe and to connect the fuel supply pipe to the chamber containing the locking piston, the pressure 10 in this chamber being released by opening a relief valve in the fuel supply pipe or in the fuel pump itself.

According to this invention the pressure chamber containing the locking piston is 15 in constant communication with the charge accumulator through a throttle-controlled pipe and the outlet from the pressure chamber is intermittently opened by means of a control gear, fuel being continuously supplied to the charge accumulator by the fuel 20 pump.

One construction according to this invention is somewhat diagrammatically illustrated by way of example in the accompanying drawing, the injection device shown being of a type suitable for use with an internal combustion engine in which the fuel is injected into the engine cylinder at the ignition dead centre of the engine piston.

Referring to the drawing, the injection device comprises a casing *a* to which fuel is supplied by a pipe *c*. The casing contains a needle valve *b* provided with a conical head *d* forming a piston against which the pressure of the fuel in the casing acts to lift the valve when the latter is released. The charge accumulator comprises an annular piston *e* which is concentric with the needle valve *b* and is held down on a shoulder 45 of the needle valve by a compression spring *f*. The upper end of the needle valve *b* is in the form of a piston and projects into a chamber *g* which is in communication on one side with the accumulator through a pipe *h* having a throttle-controlled opening *i*

and on the other side through a pipe *k* having a control gear adapted to open the outlet pipe *k* at the moment when injection is to take place.

The fuel supplied through the pipe *c* 55 raises the annular piston *e* and so compresses the spring *f*. Some of the fuel passes by the pipe *h* through the throttle valve *i* to the chamber *g* where pressure is built up and acts on the piston formed by the upper end 60 of the needle valve *b* so as to maintain the latter in its closed position. Assuming that the engine piston has at this point reached the ignition dead centre, the control gear opens the outlet pipe *k* and releases the pressure 65 in the chamber *g* thus permitting the needle valve *b* to lift under the pressure of the fuel in the accumulator.

The annular piston *e* now descends under the pressure of the spring *f* to inject the 70 fuel into the cylinder and at the end of the injection stroke the annular piston *e* reengages with the shoulder on the needle valve *b* and thus returns the valve to its seating, 75 injection being then complete.

While a certain amount of fuel will pass through the throttle valve *i* into the chamber *g* during the injection stroke of the annular piston *e*, this quantity is by reason of the short time available for its passage 80 not appreciable, and may in any case be compensated by increasing the output of the fuel pump. It will be readily understood that as the chamber *g* is connected to the fuel accumulator through a throttle valve, 85 the locking of the needle valve and accumulation and injection of the fuel can be controlled by a single control member disposed, if desired, at a distance from the apparatus 90 and in this way the operation of the device can be rendered much more reliable.

It will be appreciated that the construction above described is given by way of example only and that various modifications 95 may be effected without departing from the spirit of the invention. For example, any other suitable type of charge accumulator may be employed instead of that above described.

I claim:

In a fuel injection device for internal combustion engines the combination with a valve casing, of a fuel injection valve, an accumulator chamber on the exit-end of the injection valve, a pressure chamber on the other end of the injection valve, means for supplying the fuel under pressure to the accumulator chamber, a connecting pipe between the accumulator chamber and the pressure chamber, a throttle valve in this connecting pipe, an outlet from the pressure chamber, a valve closing this outlet and means for opening the outlet when fuel injection is to commence.

In testimony whereof I have affixed my signature.

EDUARD von SALIS.
